UNITED STATES PATENT OFFICE

100,803

DESIGN FOR A MEDALLION

Martha A. Stevens, Boston, Mass.

Application May 29, 1936, Serial No. 62,901

Term of patent 7 years

To all whom it may concern:

Be it known that I, Martha A. Stevens, a citizen of the United States, residing at Boston, in the county of Suffolk and State of Massachusetts, have invented a new, original, and ornamental Design for a Medallion, of which the following in a specification, reference being had to the accompanying drawing, forming part thereof, in which:

Fig. 1 is a face view and Fig. 2 an edge view of a medallion showing my new design.

I claim:

The ornamental design for a medallion as shown.

In testimony whereof, I have signed my name to this specification.

MARTHA A. STEVENS.
